UNITED STATES PATENT OFFICE.

ALFRED KAUFMAN, OF NEW YORK, N. Y.

HYDROCARBON-BURNER.

1,341,910.

Specification of Letters Patent.

Patented June 1, 1920.

Application filed June 19, 1919. Serial No. 305,215.

To all whom it may concern:

Be it known that I, ALFRED KAUFMAN, a citizen of Germany, but having declared my intention of becoming a citizen of the United States, and a resident of the city of New York, borough of Manhattan, in the county and State of New York, have invented a new and Improved Hydrocarbon - Burner, of which the following is a full, clear, and exact description.

This invention relates to hydrocarbon burners and has special reference to burners for kerosene or the like calculated for the development of an intense heat of a satisfactory and safe nature and with a minimum expenditure of fuel.

Among the objects therefore of the invention is to provide a heat generating burner for the combustion of kerosene or the like having provision for the initial development of heat at a flame directed laterally from a wick into a space which may be termed a mixing chamber where it is directly mixed with fresh air admitted adjacent to the flame at the wick and from below the wick and with provision for the subsequent further admixture of the gases and air with conversion of the products of initial combustion and the air to form a perfect hydrocarbon vapor in the upper portion of a larger chamber whose upper end is guarded by a relatively fine mesh screen or reticulated plate through which said vapor passes and above which said vapor is ignited and burns with a blue flame of terrific heat. The most important object therefore of the invention is to provide a simple, safe, reliable, and economic means for generating a maximum amount of heat from kerosene or similar oils, relying especially upon the mixture of the gases derived directly from the oils, with a much larger amount of oxygen than is ordinarily experienced.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which

Figure 1 is a vertical sectional view of a

generator embodying my present improvements; and

Fig. 2 is a vertical sectional detail indicating the variation in effect incident to the adjustment of the wick above its normal or best location.

Referring now more specifically to the drawings for an embodiment of my invention such as I have made and thoroughly tested, I show at 10 a tank or receptacle in which the oil 11 is carried and from which it is sent upward by capillarity through a wick 12 shown as of the well known circular or cylindrical type commonly used in kerosene burners. The means for adjusting the wick is not new but is typified by means of a shaft 13 and finger piece 14. The tank 10 is provided with a vertical funnel 15 around which the wick is located and along which the wick is adjusted from time to time as result of a very slow combustion thereof. Surrounding the wick and at the upper end of the funnel is a collar 16 the upper end of which is spaced above the level of the upper end of the funnel, said space being approximately a quarter of an inch in an ordinary size burner or perhaps slightly greater than the thickness of the wick. Without unnecessarily restricting myself to any special means for making these funnel and collar members, I show the funnel as constituting an upper extension from and integral with the bottom portion of the receptacle 10, while the collar 16 is likewise formed as an upward extension of the upper portion of the tank. The bottom of the receptacle is projected upward sufficiently far above the plane of the base upon which the device may be supported to insure free circulation of air along the bottom of the receptacle and upward through the funnel. The funnel is provided at any convenient place approximately midway between its top and bottom with a bead or shoulder 17 forming a seat or support for a sheet metal neck structure 18 of tubular form and having a bottom 19 extending inward and slightly upward from the shoulder 17 and having a large central opening 20 through which the air admitted through the bottom of the funnel is allowed to pass with comparative freedom, the movement of the air being lateral as well as upward through side openings 21 formed between the bottom member 19 and a flat baffle plate 22 supported above the central open-

ing 20. Among the purposes of the baffle plate 22 arranged in the center of the neck structure are the following: first, to spread the air admitted from beneath so that it comes into intimate contact with the gas in a relatively thin sheet in the form of a hollow cylinder as it sweeps upward along the inner surface of the perforated portion of the neck; secondly, to establish a better mixing 5 of the air and gas immediately which takes place in part directly within the neck, and thirdly to keep the neck structure from overheating. Since the cold air is deflected laterally so as to sweep along the neck structure it is obvious that the air being admitted cool will serve to subtract the heat from the neck structure, but incidentally doing so the air itself becomes somewhat warm and so enhances the thorough mixing with the gas. 10 The upper end of the neck structure 18 is open except as soon to be described and the wall of the neck structure adjacent to the upper end is provided with numerous small perforations 23 shown as arranged in parallel or horizontal circular rows. 15

Supported in any suitable manner upon the otherwise open end of the neck 18 is a chimney or dome 24 of hollow cylindrical form and somewhat larger in diameter than the neck 18. The bottom portion of this dome is formed into a rim 25 terminating in a horizontal inwardly projecting flange 26 which lies upon the upper edge of the neck 18 and constitutes a slight restriction of the opening 20 from the neck. The side walls as well as the bottom outside of the flange 26 are solid or imperforate all the way up to a beaded and flaring edge 27 which constitutes a holder for a fine mesh screen or reticulated member 28.

With the construction made substantially in accordance with the foregoing specific description its manner of use and operation may be briefly described as follows:

45 To start the generator the wick 12 is adjusted upward until it projects sufficiently far above the upper edge of the collar 16 for the application of a match thereto which obviously ignites the oil conveyed by capillarity to the upper end of the wick forming outside in this preliminary combustion a yellowish flame which would produce, except for the baffle 25, a smoke while the wick remains turned above the edge of the 50 collar as for instance in Fig. 2. As soon as the flame is extended into a complete circle around the upper edge of the wick the wick is turned down to a position substantially as shown in Fig. 1 well below the upper edge 55 of the collar 16 at which time the volume of the flame and amount of oil is materially reduced from the stage of preliminary combustion as would apply to Fig. 2. The heat, gases, and other products of combustion 60 from the wick burned as indicated in Fig. 1

all pass inward through the first and second circles of holes 23, or the lowermost portion of the holes if they are arranged other than in horizontal rows or circles, and passing thus directly into the interior of the mixing 70 chamber formed by the neck structure 18 becomes mixed with the fresh air admitted from beneath the receptacle 10 and upward through the funnel 15. This mixture of air and products of combustion from the wick 75 becomes further mixed with additional fresh air passing inward through the uppermost portion of the holes 23 or the uppermost two rows as shown, or the upper portion of the holes if they are arranged other than in 80 horizontal rows, is drawn inward into the mixing chamber by virtue of the draft caused by the upward flow of all the mixture through the dome. This air admitted through the uppermost holes 23 in passing 85 over the flame at the wick and through the metal heated thereby is warmed whereby the mixing thereof with the other air and products of combustion is facilitated within the dome. After this mixture of air in large 90 quantities with the products of combustion from the wick has taken place in and throughout the dome it passes as a thoroughly converted hydrocarbon vapor through the small perforations of the plate 95 28 and above which it is ignited by the use of a match or the like subsequent to the ignition of the flame at the wick. There is no generation of soot, smoke, or other deposit tending to blacken or clog any part of the 100 mechanism. The flame at the top of the plate 28 burns perfectly blue and with a most intense heat due to the perfect mixing with the air and the large amount of oxygen introduced into the mixture. By reason of 105 the fact that the wick does not project above the collar 16 and does not burn with a yellow flame its life is materially extended beyond that of a similar wick burned as it usually is in an ordinary kerosene burner. 110 Consequently the adjustment of the wick is resorted to only at long intervals. When the fire is to be extinguished the wick is simply turned down far enough below the position shown in Fig. 1 for it to automatically 115 extinguish itself. In this connection I wish to point out that even though the flame is burned normally at a very low elevation just within the upper edge of the collar 16 it is an impossibility for it to be blown out by 120 one's breath or a wind and neither is the flame above the plate 28 inclined to be blown out.

I claim:

1. The herein described hydrocarbon 125 burner comprising an initial gas generator, a tubular neck member within the generator space, a dome extending upward from the point of gas generation and supported by said neck member, said neck member being 130

provided with perforations at different levels, the gas passing inward therethrough at one level and fresh air passing inward at a different level, said dome being imperforate along its side walls and forming a chamber for the conversion of the products of combustion and air into a perfect hydrocarbon vapor, and a reticulated plate carried by the upper end of the dome above which said vapor may be ignited and burned with a blue flame and intense heat.

2. The herein described hydrocarbon burner comprising an initial gas generator including an inner perforate wall, a dome leading upward from the place of initial generation to a considerable distance, the dome having an imperforate base including a baffle projecting laterally over the place of gas generation and serving to guide a current of fresh air inward through said wall and above the gas, whereby the mixture of the gas and air takes place within said wall and in the center of the dome, said dome terminating in a reticulated member carried by the upper end of the dome through and above which the vapor formed by complete mixture of the products of combustion and air within the dome may be ignited and burned.

3. In a hydrocarbon burner, the combination with a receptacle for oil having a funnel for air extending upward therethrough from its bottom, a collar extending upward from the top of the receptacle and surrounding the upper end of the funnel and extending slightly above the upper end of the funnel, and a wick located in the space between the funnel and collar, of a neck structure carried by the funnel and extending above the same, the upper end of the neck being provided with numerous small lateral holes through the lowermost of which the products of combustion from the wick pass in-

ward while fresh air heated from the flame passes freely inward through the uppermost portion of said holes, a dome supported upon the upper end of the neck and into the interior of which the products of combustion and fresh air pass freely and thoroughly mix forming a hydrocarbon vapor, and means at the upper end of the dome to support an independent flame and prevent the flame from passing downward into the dome.

4. In a hydrocarbon burner, the combination with a means for carrying liquid fuel and including a vertically arranged funnel for the free upward passage of fresh air, gas generating means associated with the upper end of the funnel, a neck structure supported upon the funnel and extending above the generating means, said neck structure being provided with numerous small openings through which the gas passes inward tending to strike toward the center of the neck structure, and air baffle means within the funnel below the generating space and serving to deflect the upward currents of air through the funnel laterally so as to sweep upward along the inner surface of the neck in a hollow cylindrical form to intercept the course of the gas inward as aforesaid for immediate mixing with the gas.

5. A hydrocarbon burner of the nature set forth in claim 4 in which the air baffle means within the funnel comprises a bottom member having a large central opening, a flat baffle member centrally located above said opening, and supporting means between the bottom member and the baffle arranged in spaced relation providing a plurality of large lateral openings through which the air is deflected laterally toward the generator space.

ALFRED KAUFMAN.
